Patented Mar. 17, 1914.

UNITED STATES PATENT OFFICE.

WALTER H. HIMES, OF LANSING, MICHIGAN,

GOVERNOR FOR INTERNAL-COMBUSTION ENGINES.

1,090,212.

Specification of Letters Patent. Patented Mar. 17, 1914.

Application filed May 28, 1913. Serial No. 770,321.

To all whom it may concern:

Be it known that I, WALTER H. HIMES, a citizen of the United States, and a resident of Lansing, in the county of Ingham, State 5 of Michigan, have invented certain new and useful Improvements in Governors for Internal-Combustion Engines, of which the following is a full and clear specification, reference being had to the accompanying drawings, in which—

Figure 1 is a plan view of my device applied to a well known type of horizontal single cylinder internal combustion engine; Fig. 2 is a side elevation of the same; and, 15 Figs. 3 and 4 are detail plan views showing modifications of the push-rod engaging device.

The object of this invention is to provide simple and durable governor mechanism 20 which will operate without back-lash or lost motion and will therefore not only be sensitive and accurate in performing its function but will also be practically noiseless, as more fully hereinafter set forth.

In the drawing, the letter *a* designates the usual push-rod which when projected by the cam *b* on the cam pin or shaft *c* will open the exhaust valve in the usual manner and which when locked in its projected position 30 will hold the exhaust valve open and thus throw the engine out of cycle. It will be obvious that it is within the spirit of my invention to utilize the push-rod *a* to throw the engine out of cycle in some other manner than by holding the exhaust valve open; for instance, this rod *a* may be arranged to actuate the sparker and when held in its projected position, so as to be out of the influence of the cam *b*, it will destroy the 40 cycle by rendering the sparker inoperative.

The letter *d* designates a cam gear of the usual sort, journaled to the cam shaft *c*, and pivoted at *e* on the outer face of this gear is a centrifugally operated governor-weight 45 *f*, normally pulled inwardly toward the center of the shaft by means of a spring *g*. Rigidly attached to the weight and extending across the center of the pin or shaft *e* is a wedge-shaped arm *h*, this arm being so attached to the weight and so curved that when the weight is moved inwardly or outwardly this arm will be moved in a corresponding direction across the center of the shaft or pin *e*.

Pivoted on a lug *i* supported on the engine frame is a lever *j* one of whose ends

extends across the inclined face of the wedge *h* at a point coincident with the center of the shaft and is there provided with a pin *k* which is normally held pressed against the 60 face of the wedge, at a point coincident with the axis of the shaft, by light spring *l* connecting the lever *j* to the engine frame. The other end of the lever *j* is extended to a point adjacent to one face of the push-rod, so that 65 when this end of the lever is swung toward the push-rod it will engage behind a stop *m* carried by the push-rod and thus lock the push-rod in its cycle-destroying position.

Any suitable means may be attached to 70 the outer end of the lever *j* for engagement with the lock plate *m*. In Figs. 1 and 2 I show a flat spring *n* riveted to the lever and adapted to be adjusted by means of a set-screw *o*, this adjustment being essential in 75 order to readily vary the time of engagement of the spring *n* with the push-rod and thus regulate the speed of the engine.

Instead of using the spring *n*, I may simply use the screw shown at *p* in Fig. 3, 80 the inner end *q* of this screw being beveled to interlock with the stop block *m* on the push-rod. To take up wear and to lock the screw *p* against being jarred loose, the end of the arm may be split and clamped tightly 85 on the screw by means of a clamp screw *r*.

In the modification shown in Fig. 4, I shorten the inner end of the lever *j* and pivot thereon a supplemental lever *s* whose inner end is provided with the wedge-engaging pin *l* and whose outer end is connected to the outer end of the lever *j* by a resilient connection consisting of a set-screw *t* and a spring *u* inserted between the lever *j* and the lever *s*. With this device, adjustment of the screw *t* varies the time of engagement of the latch lever with the push-rod. The spring *u* takes up wear of the parts and prevents noise. The connection of the lever *s* to the inner end of the lever *j* may be 90 by means of a screw *v* and a coil-spring *w* for the purpose of taking up wear and preventing noise at that point. It will be observed that any other suitable means may be employed for utilizing the movement of 105 the pin *l* to lock the push-rod in its projected position.

It will be seen also that it is within the sphere of my invention to use my apparatus for operating so-called throttle-governed explosive engines as well as the hit-and-miss type. In this case the swinging lever *j* 110

would be connected to a suitable damper in the carbureter and in that manner provide for a throttling action as well as a hit-and-miss action.

5 I claim:—

1. The combination with an engine embodying a push-rod and means for projecting the same, of a wheel mounted on the engine, a centrifugally operated governor weight mounted on one face of said wheel and carrying a wedge-shaped member lying close to the face of the wheel and extending across the axis of the wheel, and a latch lever for the push-rod carrying a pin which bears upon the inclined face of said wedge member, a spring being provided to hold said pin normally against said inclined face.
- 10 2. The combination with an engine em-

bodying a push-rod, a cam for projecting the same and a gear wheel for operating said cam, of a centrifugally operated governor weight mounted on one face of said wheel and carrying a wedge-shaped member extending across the center of the wheel and having its inclined side facing away from said wheel, a latch lever for the push-rod carrying a pin extending toward the inclined face of said wedge member, and a spring holding said pin normally against said inclined face.

20 In testimony whereof I hereunto affix my signature in the presence of two witnesses.

25 WALTER H. HIMES.
